SHOE AND METHOD OF MAKING SAME

Fred Maccarone, Brooklyn, N. Y., assignor to The
Del-Mac Shoe Process Corporation, New York,
N. Y.

Application October 9, 1935, Serial No. 44,180

8 Claims. (Cl. 12—142)

My invention relates to shoes and shoemaking and more particularly to the making of flexible single soled shoes in which the upper and sole parts are secured together by stitching. Heretofore stitched shoes of this type have generally been assembled inside-out on a last and thereafter turned, and then second lasted on a different and smaller last to give the shoe its final form and shape.

10 A principal object of my invention, therefore, is to provide an improved shoe comprising a single sole, the construction of the sole and the formation of the inseam being such that the shoe may be assembled and finished right-side-out on a single last.

Another principal object is to provide a simple and economical method of making my improved shoe, and other and further objects will appear from the following specification.

20 Referring to the drawings:

Figure 1 is a plan view of a sole prepared in accordance with my invention, having an inner and outer seam channel at the forepart.

Figure 2 is a longitudinal sectional view of the sole taken on line 2—2 of Figure 1, and shows the material removed in forming the outer seam channel and in reducing the shank.

Figure 3 is a cross sectional view of the sole taken at the central ball portion thereof and illustrates the manner in which the sole edge and between substance is molded to open the inner and outer channels.

Figure 4 is a plan view of a last having the shoe upper and shank piece assembled thereon.

Figure 5 is a cross sectional view illustrating the manner in which the sole is presented to the assembly margin of the upper and the course taken by the thread in forming the forepart seam.

Figure 6 is a side elevation of the partly assembled shoe, the toe portion being shown in section to disclose the finished seam construction, and

Figure 7 is a side elevation of the finished shoe, also partly in section.

Figure 8 is a fragmental section on a larger scale, taken on line 8—8 of Figure 7 and clearly showing the seam construction of the finished shoe.

In carrying out my invention I prepare a rounded sole 10 reduced in thickness rearward of the ball line by removal of a shank piece 11, the edges through the shank portion being further reduced or feather edged at 12. The heel portion is split to form the usual heel breast flap 13 and, generally, the sole is prepared rear-

ward of the ball line similarly as soles are usually stock fitted for cement sole attaching.

Forward of the ball line I form two parallel marginal channels, being an inner channel 14 and an outer channel or groove 15 defining the intermediate between substance 16, and a channel leaf 17. The inner channel is in all respects similar to the channel formed in preparing soles for turned shoes. The outer channel, however, is an inward angular groove involving the removal of material as shown in Figure 2, the upper portion of the inner wall of the groove being substantially square to form a shoulder 18.

The inner channel is then opened in the usual manner. The outer channel is spread by moulding the edge of the sole forepart downwardly and lifting the shoulder 18, substantially to the position shown in Figure 3.

Independent of the sole preparation, the upper parts comprising the upper material 20 and lining 21, are tack lasted to a shank piece 23 and to the last 25 over the forepart. The piece 11 removed from the sole may serve as the shank piece 23 if desired. The assembly margins of the upper and its lining are then secured together over the forepart by stitching 27, the temporary lasting tacks being removed, and the surplus over-lasted material being trimmed away to produce an assembly substantially as shown in Figure 4.

Adhesive, staples or other means may be employed in place of the stitching 27, if desired, the function to be served being to form a bound edge which will hold the upper over the last after removal of the lasting tacks and which will be insertable into the outer channel or groove 15.

The assembly margin 30 of the upper forepart, bound by the securing means 27, is then brought into position in the outer channel 15 and there secured by stitching, the thread 35 of which passes into the outer channel, through the upper parts and between substance 16 and into the inner channel. During the stitching operation the last may be removed, if desired.

In stitching the shoe on the last by hand it is necessary to pass the inside thread between the last and the sole in forming each stitch. This may be done by passing the inside thread along between the adjacent surfaces of the sole and the last and out where the marginal portions of the upper have not yet been sewn to the sole. In completing the seam about the forepart, the inside thread is passed out from under the shank portion of the sole.

If the last 25 is removed, it is reinserted after

the forepart stitching has been accomplished and the shank and heel portions of the sole are layed down and secured in position by means of a suitable adhesive, pyroxylin cement being preferred, after which an even pressure is applied over the entire sole area and maintained until the cement has set. This pressure is preferably obtained in a standard cement sole attaching machine. The application of pressure over the forepart conforms the sole, including its previously moulded edge, to the last bottom and causes the channel leaf 17 and shoulder 19 to close over the thread and parts in the respective channels, obtaining a smooth interior for the shoe.

15 To complete the shoe, a heel 40 is attached in the usual manner, the last 25 is removed and a sock lining 41 is inserted.

The shoe, constructed right side out on a single last, obtains all the advantages of a turned 20 shoe and is not subjected to the usual deleterious second lasting operations in which a second last of different size is inserted. At the forepart the shoulder 19 abuts flushly against the upper lining to hold the shoe in its lasted 25 shape. The upper lining fits snugly and has no tendency to wrinkle up and, in other respects, the advantages of welt and McKay shoe constructions are combined with the advantages inherent in turned shoes.

30 Having thus described my invention, I claim:
1. In shoemaking methods, that improvement which includes: stitching the forepart of an upper right-side-out to the forepart of a single sole and then cement attaching the shank and 35 heel portions of the sole.

2. In shoe making, that improvement which includes: providing a rounded sole blank with two marginal channels, defining an intermediate between substance, positioning the sole assembly 40 margin of an upper right side out in the outer of said channels and securing said margin against the inner wall of the outer channel by means of stitching extending through the upper and said between substance.

45 3. In shoe making, that improvement which includes: providing a rounded sole blank with two marginal channels defining an intermediate between substance, the inner wall of said outer channel being formed with an outwardly 50 projecting shoulder-like flange and the outer wall of the inner channel carrying a channel leaf, positioning the sole assembly margin of an upper in the outer of said channels and securing it against the inner wall of said outer channel 55 below said flange by means of stitching extending through the upper and said between substance.

60 4. In shoemaking methods, that improvement which includes: lasting an upper right-side-out, binding the overlasted assembly margin of the upper and freeing said margin from the last, providing a full rounded sole having therein a leafed channel and a marginal groove outwardly of said channel, said groove and channel defining an intermediate between substance, po-

sitioning the assembly margin of the upper in said groove and securing it to the sole by stitching extending through the upper and said between substance.

5 5. In shoemaking methods, that improvement which includes: temporarily attaching a shank piece to a last and lasting an upper right-side-out to said shank piece and to the last forwardly of the shank piece, binding the overlasted assembly margin of the upper forepart and freeing said forepart margin from the last, providing a full rounded sole having a leafed channel and a marginal groove outwardly of said channel in the forepart thereof, the inner wall of said groove being formed to comprise a shoulder-like flange, said groove and channel defining an intermediate between substance, positioning the forepart assembly margin of the upper in said groove and securing it to the sole by stitching extending from the groove below 20 said flange through the upper and said between substance into said leafed channel, and then cement attaching the sole over the shank and heel areas of the shoe.

6 6. In shoe making, that improvement which includes providing a sole having two parallel marginal channels in its forepart, the inner of said channels being a leaf channel and the outer of said channels being an angular groove having its inner wall undercut to define a shoulder, 30 positioning the sole assembly margin of an upper forepart right-side-out in the outer of said channels and securing said margin against the inner wall of the outer channel below said shoulder by means of stitching extended through the 35 upper and said between substance, and then cement attaching the sole rearward of the forepart.

7 7. A shoe comprising a sole member having two marginal channels in the inner surface 40 thereof, said channels defining an intermediate between substance, and the inner wall of said outer channel forming a shoulder, an upper having straight edge margins extending into the outer channel and faced against said shoulder, 45 stitching extending through the upper and said between substance, and a channel leaf carried by said between substance and overlying the stitching in said inner channel.

8 8. A shoe having a single sole and an upper secured thereto by stitching over the forepart and by adhesive over the shank portion, said sole having two marginal channels formed in the inner surface of the forepart thereof, said channels defining an intermediate between substance, and the inner wall of said outer channel forming a shoulder, said upper having straight edge margins extending into the outer channel and faced against said shoulder, stitching extending through the upper and the between substance, and a channel leaf carried by the between substance overlying the stitching in said inner channel.

FRED MACCARONE.
